F. EVANS & D. DUTT.
TRIP FOR RAILWAY SWITCHES.
APPLICATION FILED MAR. 24, 1917.

1,253,802.

Patented Jan. 15, 1918.

UNITED STATES PATENT OFFICE.

FRANK EVANS AND DAVID DUTT, OF RIVERDALE, MICHIGAN, ASSIGNEES OF ONE-
THIRD TO BURTIS O. MARKHAM, OF RIVERDALE, MICHIGAN.

TRIP FOR RAILWAY-SWITCHES.

1,253,802.

Specification of Letters Patent. Patented Jan. 15, 1918.

Original application filed September 23, 1915, Serial No. 52,174. Patent No. 1,223,945, dated April 24, 1917.
Divided and this application filed March 24, 1917. Serial No. 157,117.

To all whom it may concern:

Be it known that we, FRANK EVANS and DAVID DUTT, citizens of the United States, and residents of Riverdale, in the county of 5 Gratiot and State of Michigan, have invented a new and Improved Trip for Railway-Switches, of which the following is a full, clear, and exact description.

Our invention relates to automatic railway switches adapted to be operated by a 10 train trip, that is to say, a trip mounted on a locomotive, or in the case of street railways, on a car.

Our present application is a division of 15 an application filed by us September 23, 1915, on which Letters Patent No. 1,223,945 were issued April 24th, 1917.

Objects of the invention are to provide a 20 trip having a resiliently sustained contact member to engage the track devices; and to provide a resilient train trip of strong and simple construction that may be readily mounted on the locomotive or car.

The invention will be particularly explained in the specific description following.

Reference is to be had to the accompanying drawings forming a part of this specification in which similar reference characters indicate corresponding parts in all the 30 views.

Figure 1 is a side elevation of a locomotive equipped with my improved trip, the view including track devices;

Fig. 2 is a plan view showing one form of 35 track devices to be operated by the trip;

Fig. 3 is a detail sectional side elevation of the switch-operating device in the track to be engaged by the trip;

Fig. 4 is a detail side elevation of the trip.

40 In the illustration the letter A represents a main track; B, a siding; C, switch points; and D, a locomotive on which our improved trip, designated generally by the numeral 20, is mounted.

45 The switch, which forms the subject matter of our application referred to above and to be operated by the trip 20, includes a switch bar 10 disposed transversely beneath the switch points and suitably connected 50 with the latter. Said switch bar is mounted to rock and to slide axially in any suitable bearings 13. The switch bar 10 has a rocker arm 14 thereon extending upwardly above the track and passing freely through a verti-

cal opening 15 in an elongated link 16 which 55 ranges longitudinally of the track. In the example shown the arm 14 has a slot 14^a therein through which a pin 15^a extends to opposite side walls of the opening 15. One end of the link 16 is pivoted as at 16^a to a 60 lever 17 which is fulcrumed at its lower end as at 18 to any suitable block 19. The opposite end of the link 16 is pivoted as at 16^b to the lower end of a similar lever 17^a fulcrumed between its ends as at 18^a to a bracket 65 19^a or the like. The arrangement is such that when the lever 17^a is tripped and rocked on its fulcrum by the trip 20 approaching the same from the direction as indicated in Fig. 1, the links 16 will be drawn toward 70 said lever. On the other hand when the opposite lever 17 is tripped and rocked on its fulcrum by a train moving in the opposite direction, a pushing action will be exerted on the link 16. 75

The trip 20 serves to engage a lever 17 or 17^a by a train running at any rate of speed. Our improved trip includes a hanger 22 which is suspended from one arm of a bellcrank lever 23, the other arm of said lever 80 being connected by a rod 24 with a hand lever 25 in the engine cab. The contact member 26 of the trip consists of a face plate hung at its upper end as at 27 between ears 28 on the hanger 22. Between the said face plate 85 and the front of the hanger 22 is interposed a compression spring 29 which thereby resiliently sustains the face plate 26 to cushion the blow of the latter against a lever 17 or 17^a of the track devices, the purpose being 90 to prevent damage to the trip 20 or to the track devices while insuring an effective engagement thereof.

In practice means are provided whereby the rocking of the switch bar 10, by the link 95 16, will result in an axial sliding movement of said switch bar as fully explained in our above-named application.

The hanger 22 has guided movement on any suitable fixed member 30 of the locomotive or car, whereby to move vertically in response to the rocking of the bellcrank lever 23.

Having thus described our invention, we claim as new, and desire to secure by Letters 105 Patent:

1. A trip adapted to be mounted on a locomotive or car to automatically actuate a

railway switch, said trip including a hanger, means to mount the hanger on a car in position for vertical movement, a face plate constituting the contact element of the trip, a 5 spring interposed between the contact member and the hanger, and means to raise and lower said trip.

2. A trip adapted to be mounted on a locomotive or car to automatically actuate a railway switch, said trip including a hanger, means to mount the hanger on a car or locomotive, a face member constituting the contact element of the trip, and pivoted at its 10 upper end to the said hanger, and a spring

interposed between the said face member at 15 its lower end and the said hanger.

3. A trip adapted to be mounted on a locomotive or car to engage track devices for operating a switch, the said trip including a hanger, means to mount the hanger on a car or locomotive to slide vertically, a bell-crank lever from which said hanger is suspended, means to actuate the said lever, and a face member on the hanger, and constituting the contact element of the trip. 20

FRANK EVANS.
DAVID DUTT.
